(57) **CLAIM**

The ornamental design for a sculpted top sculpted cup tray, as shown and described.

DESCRIPTION

FIG. 1 is a top isometric view of a sculpted top squared cup tray showing our new design.

FIG. 2 is a bottom isometric view thereof.

FIG. 3 is a bottom view thereof.

FIG. 4 is a top view thereof.

FIG. 5 is a left side view thereof.

FIG. 6 is a right side view thereof.

FIG. 7 is a front view thereof; and,

FIG. 8 is a rear view thereof.

The broken line portions of the disclosure are for illustrative purposes only and form no part of the claimed design.
